METHOD AND APPARATUS FOR PACKAGING

Almon J. Cordrey and Melvin Wagner, Chicago,
Ill., assignors to The Liquid Carbonic Corpora-
tion, Chicago, Ill., a corporation of Delaware

Application February 10, 1938, Serial No. 189,834

50 Claims. (Cl. 93—6)

This invention relates to packaging machines and methods of packaging materials, and in particular, to methods and apparatus for packaging materials which are preferably sealed in their containers.

One object of this invention is to provide a packaging machine, wherein the material is inserted in the package simultaneously with the forcing of a non-oxidizing gas into the package for the purpose of forcing out the air which would otherwise cause oxidation or deterioration of the contents.

Another object is to provide a packaging machine, wherein comminuted materials are fed into a container while a gas is likewise being forced into the container to displace the air therefrom, after which the filling entrance of the container is closed automatically and sealed by the application of heat.

Another object is to provide a packaging machine, wherein means is provided for the filling of a bag-like container with material to be packaged while a gas is fed into the container near the bottom thereof to displace the air from the container, whereupon the mouth of the container is closed by elements which, while effecting this closure, also force out much of the remaining gas at the top of the container and thereafter seal the closed container by means of heat, whereupon the sealed mouth of the bag-like container is pressed down and folded over.

Another object is to provide a packaging machine, wherein cartons are caused to be moved successively through filling, sealing and tucking stations, the carton on its arrival at the filling station being provided with a bag-like container which is simultaneously filled with the material to be packaged while a gas is forced into the container to drive out the air. After the carton and container have thus been assembled and filled, means is provided for moving the carton and container to the sealing station, where the mouth of the bag is automatically spread apart in order to force the remaining air and gas from the bag, and sealing elements are brought into engagement with the bag adjacent its mouth in order to seal the mouth. Means is then provided for moving the carton and the sealed bag to the tucking station, where the sealed mouth of the bag is pressed downwardly into the carton, and the end flaps of the carton moved inwardly to hold the bag taut in its depressed position until the side flaps are moved inwardly to permanently maintain this closure.

Another object is to provide a method of pack-

aging materials consisting in forcing a gas into the container to displace the air while the container is being filled with the material so as to prevent the subsequent oxidation or deterioration of the material arising from the presence of air in the container.

Another object is to provide a method of packaging materials, wherein the mouth of the container is spread apart prior to its being sealed so as to expel the major portion of the gases remaining in the top of the container, and then sealing the mouth of the container while it is so spread apart.

Another object is to provide a method of packaging materials comprising inserting a bag-like container in a carton or similar outer inclosure, filling the container with the material to be packaged while forcing a gas therein so as to expel the air from the container, and then distending the mouth of the container to expel the gas remaining at the top of the container, and thereafter sealing the thus distended mouth by bringing the opposite edges of the container together under the influence of heat.

In the drawings:

Figure 1 is a perspective view of the packaging machine of this invention, showing the bag holder in its raised position prior to placing of a bag thereon.

Figure 2 is a perspective view of the machine shown in Figure 1, but showing the bag holder and bag half lowered into the carton.

Figure 3 is a perspective view of the packaging machine shown in Figures 1 and 2, but showing the bag completely lowered into the carton in position for filling the bag with the packaged material while introducing a gas for expelling the air.

Figure 4 is a general perspective view of the packaging machine, showing its relationship with the conveying mechanism and other machinery with which the packaging machine may be used, a bag being in position upon the bag holder.

Figure 5 is a side elevation of the filling portion of the packaging machine.

Figure 6 is a rear elevation of the filling portions of the machine shown in Figure 5.

Figure 7 is a side elevation of the sealing portion of the machine with the sealing elements open.

Figure 14 is a diagrammatic cross section of the filling portion of the machine, showing the bag holder rest prior to the application of the bag.

Figure 15 is a view similar to Figure 14, but with the bag holder and bag at the instant of entering the container.

Figure 16 is a view similar to Figures 14 and 15, but showing the bag holder and bag at their lowest point of travel.

Figure 17 is a view similar to Figures 14 to 16, but showing the bag holder being withdrawn from the carton while the bag is being filled and gas is being introduced.

Figure 18 is a view showing the filled bag and container in position for sealing.

Figure 19 is a diagrammatic view showing the mouth of the bag distended by the mechanical fingers prior to its being sealed.

Figure 20 is a diagrammatic cross section at right angles to Figures 14 to 19, showing the sealing elements moving into their sealing position while closing the mouth of the bag.

Figure 21 is a diagrammatic view similar to Figures 14 to 19, showing the top of the bag pressed downwardly while an end flap is being forced inwardly to tuck the bag top within the carton mouth.

Figure 22 is a diagram showing the operating cycle in the filling portion of the machine.

Figure 23 is a diagram similar to Figure 22, but showing the operating cycle in the sealing portion of the machine.

Figure 24 is a view similar to Figures 22 and 23, but showing the operating cycle in the tucking portion of the machine.

Figure 25 is a diagrammatic view, similar to Figure 21, but showing a further stage in which a movable tongue holds down both end flaps of the carton as the latter moves to the sealing station.

General arrangement

In general, the packaging machine of this invention consists of a conveyor which moves a carton step-by-step successively through a plurality of stations, the three concerned with the present invention being a filling station, a sealing station and a tucking station. A carton bottom sealing station at the back of the machine precedes the filling station, but forms no part of the present invention. The portion of the machine at the filling station is provided with a bag holder, upon which a bag is placed by the operator while the bag holder projects forwardly at an angle. The bag holder is then retracted automatically to a vertical position. Previously, the material to be packaged has been placed in a hopper in the upper part of the filling portion of the machine, where it is automatically measured out and a charge of predetermined weight delivered to the bag holder. The bag holder and bag then are moved downwardly by automatic mechanism so that the bag enters the carton, which by this time, has arrived beneath the bag holder and halted.

As the bag holder descends a gas is introduced into the bag and flushes out the air in the bag. This gas is preferably of a non-oxidizing nature relatively to the material being packaged. For packaging coffee carbon dioxide gas has been found suitable as its presence is not detrimental to the coffee, as is the case with air. The gas starts flowing at any desired instant, such as after the bag holder has reached its vertical position and until the bag is just entering the carton. As the bag holder descends into the carton the material is dropped into the bag while the gas is still flowing. The flow of coffee and gas may conveniently commence at substantially the same time.

Meanwhile, the bag holder parts have spread apart (Figure 5), thereby forming the bag to fit the carton while still coming down. When the bag holder reaches the bottom position it dwells there for a short time, such as one and a half seconds, and then is moved upwardly, with the gas and material still flowing. When the bag holder has traveled upwardly about one-half of the height of the carton, the gas is automatically cut off but the material continues to flow until it fills the bag.

The conveying mechanism then comes into play to move the filled bag and carton to the sealing station, where two fingers descend into the mouth of the bag and move outwardly to distend it. This distending operation assists in forcing the gases from the space at the top of the bag, and at the same time prepares the bag for sealing. When the fingers have spread the mouth of the bag prior to sealing it, the end flaps of the carton are out in a straight line (Figure 19). The fingers are then mechanically withdrawn while electrically heated sealing elements move into engagement with the opposite sides of the bag at its mouth, sealing the top of the bag tightly together by heat-fusing its opposite edges.

The conveying mechanism now resumes its motion and conveys the carton and sealed bag to the tucking station. Here the sealed top of the bag is pressed downwardly and tucked inwardly by mechanism moving an arm which forces one of the end flaps of the carton inwardly and downwardly while the tucking member is being withdrawn with a wiping motion. After this occurs, a second arm moves over and tucks down the other end flap, whereupon the conveying mechanism again comes into operation, and conveys the carton outwardly beneath the second arm while the first arm moves away, thereby holding down both end flaps of the carton. This completes the tucking operation and places the carton in position for the sealing of the carton by subsequent mechanism, which forms no part of the present invention. Meanwhile, the side flaps of the carton have been held open by stationary rods so that the sealing and tucking operations can take place without interference from the side flaps. When the carton passes beyond the tucking portion of the machine, however, the side flaps are released and are then pressed together and glued by subsequent mechanism, forming no part of the present invention.

Conveying mechanism

Referring to the drawings in detail, Figure 4 shows the entire machine, together with other mechanism forming no part of the present invention. Figure 4, however, shows the relationship of the machine to this other mechanism, and

Filling mechanism

is inserted for that purpose. In Figure 4 empty cartons are conveyed to the packaging machine upon a belt conveyor 10 and the filled cartons conveyed from the machine upon a belt conveyor 11. The packaging machine is supported upon a base 12, having uprights 13 upon which the subframe 14 of the machine is supported. The mechanism shown beneath the subframe 14 forms no part of the present invention other than to drive not only the filling, sealing and tucking portions of the packaging machine, but also the remaining portions not included in the present invention.

A motor 15, mounted upon the uprights 13, carries a pulley 16 with a belt 17 driving a pulley 18 upon a shaft 19. The latter carries an eccentric 20 with a surrounding collar 21, connected to a tamping rod 22 which operates against a spring 23 to tamp the bottom of the carton while it is being filled with material. The tamping member 24, mounted on the rod 22, moves up and down under the influence of the eccentric 20, and taps or jars the machine so that the material in the carton is caused to settle down more evenly therein and become more solidly packed. The tamping mechanism is supported upon a frame 25 depending from the subframe 14, and is connected to a rectangular frame 26 immediately over the motor 15.

Mounted at opposite ends of the subframe 14 are pairs of spaced upper and lower sprockets 27 and 28, carrying upper and lower conveyor chains 29 and 30, respectively, (Figure 4). The sprockets are mounted upon shafts 31 and 32, journaled in the subframe 14 and rotated intermittently by mechanism not shown in detail. Secured to the conveyor chains 29 and 30 are upper and lower conveying members 33 having arms 34 projecting therefrom for receiving and conveying cartons 35, placed therein. The conveying members 33 are slotted to permit the adjustment of the arms 34 to different sizes of cartons 35.

Mounted on the base 12 (Figure 4) is a main cam housing 1 containing main cams which are driven to impart step-by-step motions to various parts of the machine. This cam mechanism in its details forms no part of the present invention, but drives a shaft 2 rising from the housing 1 to operate the drive shaft 41 through bevel gearing at 41a (Figure 2). Rising from the housing 1 (Figure 4) are other shafts 3 and 4, respectively operating a carton bottom sealer on the back of the machine, and a carton top sealer on the front of the machine. The first sealer precedes and the last sealer follows the mechanism units of the present invention, and are thus outside the present invention. Depending from the main cam housing 1 is a shaft 5 which drives shafts 6 and 7, carrying sprockets 8, interconnected by the sprocket chain 9, this mechanism, in turn, driving the vertical shaft 32 which drives the right-hand conveyor sprockets 27 and 28. In this manner a step-by-step motion is imparted to the conveyor chains 29 and 30 which convey the cartons 35 from station to station.

A rail 36 extends above the subframe 14, the outer portion of which serves as a guide for the sides of the cartons 35 to keep them properly positioned in the conveyor pockets as the cartons 35 are moved in an orbital path step-by-step by the conveyor chains 29 and 30. Mounted upon the subframe 14 and spaced thereabove is a base 37, upon which the major elements of the machine are supported.

The filling portion of the machine (Figures 1 to 6) consists of a vertical frame 38 mounted upon the base 37 and rising upwardly therefrom. Supported forwardly on the frame 38 are guide members 39, which serve to guide the vertical reciprocation of the bag holder, as subsequently described. The frame 38 is provided with cross members 40, in which is journaled a drive shaft 41. The drive shaft 41 is driven by bevel gearing at 41a (Figure 2) from the shaft and extends longitudinally through the filling, sealing and tucking portions of the machine, and is supported at its opposite end by a bearing bracket 42 (Figure 4) rising upwardly from the base 37.

Mounted on the drive shaft 41 is a disc 45 (Figure 5), provided with a cam groove 44 on its inner face (Figure 3). The cam groove 44 serves to receive a roller 45 mounted upon a threaded stud 46, secured by a nut 47 (Figure 6) to a link 48. The latter is provided with a slotted portion 49 (Figure 5) through which the drive shaft 41 passes. The rearward end of the link 48 is pivotally connected, as at 50, to an arm 51 mounted upon a counter-shaft 52, journaled as at 53, in the frame 38 (Figure 5). Secured to the counter-shaft 52 is the rearward end of an arm 54 (Figures 5 and 6), the forward end of which is pivotally connected to a shaft 55. Depending downwardly from the shaft 55 are links 56, the lower ends of which loosely pivot upon a rod 57, mounted upon the bag holder carriage 58. The bag holder carriage 58 extends between the vertical guide members 39 (Figure 1) and reciprocates vertically under the guidance of these guide members. The forward side of the bag holder carriage 58 is provided with a rod 59, similar to and parallel with the rod 57.

Mounted upon the bag holder carriage 58 are pivot pins 60 (Figure 5), upon which the bag holder 61 is pivotally mounted. The bag holder 61 carries arms 62, terminating at their upper ends in rollers (not shown), which engage vertical cam grooves 63 on the inner walls of the guide members 39 (Figure 3). The upper portions of the cam grooves 63 are directed rearwardly, as at 64, (Figure 3) so that when the bag holder 61 is raised the rollers on the ends of the arms 62 will move rearwardly, tilting the lower portion 65 of the bag holder forwardly 50 around its pivot pins 60. The lower portion 65 of the bag holder 61 is provided with a downwardly extending framework 66, of a rectangular shape, adapted to enter a bag 60, the mouth of which is releasably held upon the portion 65 by means of the spring clip 67. The bag-holding framework 66 has relatively movable parts 66a and 66b, which move apart to shape the bag to the carton 35 as the bag-holding frame 66 descends. The bag holder 61 likewise carries a gas discharge pipe 68, the lower end of which terminates near the lower end of the frame 66, and the upper end of which is connected to a pipe 69, which serves to convey gas to the discharge pipe 68. The air displaced by this gas escapes through the open top of the bag. The bag holder 61 is likewise provided with an auxiliary gas connection plug 70, through which gas may be introduced independently for experimental or testing purposes.

The flexible pipe 69 (Figure 1) runs rearwardly to an outlet connection 71 (Figure 6) leading into a valve 72. Projecting upwardly from the valve 72 is a valve rod 73 (Figures 5

and 6) adapted to be engaged by the lower edge of the arm 74 (Figure 5). The rearward end of the arm 74 is pivoted, as at 75, upon the support 76 (Figure 6), and its forward end carries a roller 77 (Figure 5) which engages the lower edge of a cam 78. The valve 72 is likewise provided with an inlet connection 79, to which is attached a flexible pipe 80 leading to the pressure-reducing and regulating valve 81, attached 10 to the end cap 82 of a gas cylinder 83. A pressure gauge 84 serves to indicate the pressure of the gas being blown into the bag 160 through the line 69 leading thereto from the cylinder 83. The cam 78 serves to operate the valve-operating arm 74 to move the valve rod 73 and operate the gas valve 72, in accordance with a predetermined cycle of operations, as hereinafter explained. Similarly, the rotation of the disc 43 serves to move the roller 45 and arm 48 in and out, thereby 15 moving the arm 54 up and down in an angular path so as to cause the bag holder 61 to move up and down along its guide members 39, in accordance with a predetermined cycle of operations. The counter-shaft 52 also carries an arm 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

motor 89 and spills coffee from its grooves into the scale bucket. This weighing mechanism is operated independently of the rest of the machine.

At the proper time, determined by the rotation of the cam 141, the latter operates the rod 136 to open the bottom 130 of the bucket 116, so that the coffee falls into the bag 160 at about the time the bag is half-way into the carton. After the coffee is dumped in this manner, the counter-weights 111 raise the scale bucket and the rod 122 releases the dog 123. The rod 147 is now operated by the cams 150 to reengage the friction clutch 124. The friction clutch 124 then again engages and operates the feeder roll to weigh out the next portion of coffee.

The bottom of the bucket 116 is closed by a gate 130, having upwardly extending arms 131 secured to a shaft 132 mounted in the bracket 102. The outer end of the shaft 132 carries an arm 133 (Figure 5), to the outer end of which is pivotally attached, as at 134, the connection 135 of a rod 136, the lower end of which is threaded into a slotted bar 137 through the slot 138 of which the drive shaft 41 passes. The lower end of the bar 137 carries a pivot stud 139, on which is mounted a roller 140 engaging the lower edge of a cam 141 mounted upon the drive shaft 41. Consequently, when the drive shaft 41 rotates, the cam 141 causes the rod 136 to move downwardly, thereby opening the gates 130 and permitting the material to flow from the bucket 116, into the receiver 142, attached to the upper part of the bag holder carriage 58. The receiver 142 is provided with a guard 143, extending upwardly therefrom (Figure 1) to guide the coffee or other material into the receiver 142, from whence it passes downwardly into the top of a funnel 144 opening into the bag holder 61.

The operation of the measuring apparatus within the housing 91 is regulated by an arm 145, to which is attached a yoke 146 on the upper end of a rod 147 (Figure 4), the lower end of which is threaded into a slotted bar 148, similar in construction to the slotted bar 137 previously described, and similarly carrying a roller 149 engaging the lower side of a cam 150 mounted upon the drive shaft 41 (Figure 6).

The operation of the filling portion of the machine is described hereinafter in detail. To initiate the operation, however, the operator places upon the frame 66 a bag 160 (Figure 4), this bag being held releasably in position by the spring clip 67. As the drive shaft 41 rotates the motion of the arm 54 causes the bag holder carriage 58 and bag holder 61 to move downwardly, first assuming the vertical position by reason of the action of the cam grooves 63 (Figure 3). The bag 160 moves downwardly into the carton 35 while the cam 78 operates the gas valve 72 to admit gas through the discharge pipe 68, into the bag, thereby flushing out the bag as it is lowered into the carton 35. Meanwhile, a measured charge of coffee or other material flows out of the receiver 142, through the funnel 144 and lower portion 65 of the bag holder 61, into the bag 160, filling the bag, which has now reached the bottom of the carton 35.

The further action of the mechanism, particularly the cam disc 43, raises the arm 54 and with it the bag holder carriage 58 and the bag holder 61. The bag 160 slips from beneath the spring clip 67 and remains in the carton 35. As the bag holder 61 reaches a position approximately half-way out of the bag 160 and carton 35, the

Mounted in the upper part of the frame 38 is an auxiliary frame 88 (Figure 5), which serves to support a motor 89 for driving the feeding and measuring portion of the apparatus. The material to be packaged, such as coffee, is placed in a hopper 90, at the top of the filling portion of the machine (Figure 5), and passes downwardly into a housing 91 secured to the auxiliary frame 88 on its forward side. Journalled in this housing 91 is a cross shaft 92, upon which is mounted a rotary measuring element 93, operated by a sprocket 94 (Figure 6) and a sprocket chain 95 from a drive sprocket 96 upon a shaft 97. The latter is journalled upon the forward side of the housing 91 (Figure 5) and carries a pulley 98, which is driven by a belt 99 from the pulley 100 on the motor shaft 101.

Mounted upon the top of the frame 38 is a bracket 102 having upper and lower arms 103 and 104, respectively provided with limiting stop screws 105 and 106. These stop screws 105 and 106 serve to limit the reciprocation of a yoke-shaped lever 107 which is pivotally mounted, as at 108, upon the bracket 102. The rearward end 55 of the lever 107 is engaged by a U-shaped yoke 109, to which is attached a hook 110 terminating in a weight 111 (Figures 5 and 6). The upper, rearward portion of the lever 107 is provided with an L-shaped member 112 having a threaded portion 113, upon which is mounted a threaded weight 114. By rotating the latter the effect of the weight 111 upon the lever 107 may be varied. Mounted between the forward ends of the yoke-shaped lever 107 upon the pivot pins 115 is a container or bucket 116.

When the scale bucket 116 becomes loaded with its predetermined weight, it falls by overcoming the counterweights 111. In falling it lowers rod 122 (Figure 6), which engages a dog 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

cam 78 closes the gas valve 72 and cuts off the further discharge of gas through the discharge pipe 68. When the bag holder 61 has completely passed out of the bag 160 and carton 35, the conveyor chains 29 and 30 resume their intermittent motion and move the filled carton to a position beneath the sealing portion of the machine, halting at this point. By the same motion a second carton 35 is brought into position beneath the filling portion of the machine. Meanwhile, the side flaps of the cartons 35 are forced open and downwardly by the flap-opening rods 117 and 118 (Figure 1), the forward ends of which are mounted upon a bar 119, secured to the frame 38. The rearward ends of the rods 117 and 118 are connected to a bar 120, secured at its opposite ends to the brackets 121 (Figure 1). The latter are mounted upon the base 37.

Sealing mechanism

Referring to Figures 7 to 9, the sealing portion of the machine is mounted upon brackets 161 and 162 (Figure 9), supported upon the base 37 of the machine. The bracket 162 has twin arms 163 and 164 which are centrally located between the brackets 161. Pivot shafts 163 and 164 are arranged at the top and mid-portions of the bracket 162, and serve respectively to pivotally support a pair of parallel links 165 and 166. These parallel links are interconnected by the vertical portions 167 of an inverted T-frame, generally designated 168, and having pivots 169 and 170, respectively, (Figure 10). The cross bar 171 of the inverted T-frame 168 is provided with bag-spreading fingers 172, in the form of levers.

The bag-spreading fingers 172 are pivotally mounted, as at 173, and on their upper ends carry pins 174 with rollers 175 arranged to engage vertical fixed cam members 176, having inwardly projecting portions 177 at their lower ends. The fingers 172 are urged inwardly at their lower ends by springs 178 (Figures 2 and 10) so that the rollers 175 are urged constantly into engagement with the vertical cam members 176. The lower parallel link 166 is in the form of a lever having a roller 179, rotatably mounted at its rearward end (Figure 7). The roller 179 engages the lower edge of a rotary cam 180. As a result of the rotation of the cam 180, the roller 179 moves up and down and causes the inverted T-frame 168 to rise and fall, in accordance with the configuration of the cam 180. When the T-frame 168 is at the top of its path, the rollers 175 on the fingers 172 engage the upper portions of the vertical cam members 176 and permit the lower ends of the fingers 172 to be urged inwardly toward one another by the springs 178. When the T-frame 168 approaches the lower limit of its travel, however, the rollers 175 engage the projections 177, and the lower ends of the fingers 172 are urged apart, thereby distending the bag which they have meanwhile entered.

The vertical cam members 176 are secured at their upper ends to the portions 181, which in turn form the upper ends of the brackets 161. Journalled in these portions 181 are spaced parallel shafts 182 and 183 (Figures 7 and 9) respectively supporting downwardly depending pairs of arms 184 and 185. Mounted on the shafts 182 and 183 are intermeshing quadrant gears 186 and 187, whereby the shafts 182 and 183 are rotated in opposite directions. This is accomplished by means of an arm 188 mounted on the shaft 182 (Figures 7 and 9), and having a pivot pin 189 to which is secured the forward clevis 190

of a link 191, the rearward clevis 192 of which is pivotally secured, as at 193, to the upper end of an arm 194, the lower end of which is pivoted on a shaft 195 extending between the brackets 161. At an intermediate point the arm 194 is 5 provided with a stud pin 196 carrying a roller 197, which engages the lateral edge of a cam 198 mounted upon the drive shaft 41. A coil spring 199, secured at its forward end in the hole 200 of the arm 194 and at its rearward end to the 10 bracket 201 mounted on the base 37, tends to close the arms 184 and 185 and the electrically heated sealing elements 203 and 202 thereon. The spring 199 also urges the roller 197 into engagement with the cam 198. 15

The spacing of the sealing elements 202 and 203 is regulated by a pair of stop screws 204 and 205 (Figure 8). The sealing elements 202 are provided with dove-tailing portions consisting of an indentation 206 on the rearward element 202, 20 and a projection 207 on the forward element 203. These portions engage the mouth of the bag and cause it to be securely sealed by reason of the electrical heating elements (not shown) within the sealing elements 202 and 203. The heating 25 elements are connected by the conductors 208, 209 and 210 to the junction box 211, and interconnected by the conductor 212 (Figure 1). The arms 184 and 185 are additionally urged toward one another by the coil springs 213 (Figure 7). 30 From the junction box 211 electrical conductors 214 and 215 run to any suitable source of current supply for energizing the electrical heating elements of the sealing elements 202 and 203 (Figure 1). 35

As a consequence of this construction, when the drive shaft 41 is rotated, the cam 198 will cause the link 191 to move outward and the spring 199 will cause it to move inward, thereby causing the sealing elements 202 and 203 to approach and recede from one another. The cycle of operations by which the sealing elements 202 and 203 cooperate with the motion of the bag-distending fingers 172 is set forth in detail below. It will be seen, moreover, that as the sealing elements 202 and 203 approach each other upon arcuate paths they engage the top of the bag near its mouth, and tend to force out such gas as may be remaining in the bag above the material which has been packed therein by the filling mechanism. 50

Tucking mechanism

When the sealing of the bag has been completed by the action of the sealing elements 202 and 203, after the bag-distending fingers 172 have performed their function of distending or elongating the mouth of the bag, the conveyor chains 29 and 30 again start in motion and convey the carton 35 and the now sealed bag 160 to the tucking station (Figures 11, 12 and 13). Here 60 the conveying mechanism halts and the tucking mechanism comes into play. The tucking mechanism (Figures 11, 12 and 13) is mounted upon a frame 220 (Figure 12), on the upper end of which is mounted a pivot shaft 221. Pivotally 65 mounted upon the latter is an arm 222, intermediately provided with a stud 223 carrying a roller 224. The latter engages the upper edge of a cam 225, mounted upon the drive shaft 41. At its outer end the arm 222 is provided with 70 a pivot pin 226, to which is pivotally attached a plunger 227 having on its lower end a flat pressing member 228. Intermediately the plunger 227 is provided with a pivot pin 229, to which is connected the forward clevis 230 of a link 231, the 75

rearward end of which is secured to a slotted bar 232 (Figure 13), through which the drive shaft 41 passes. On its rearward end the slotted bar 232 is provided with a stud 233 carrying a roller 234 engaging the rearward edge of a cam 235, mounted upon the drive shaft 41. A coil spring 236, secured as at 237, to the slotted bar 232 and at its forward end to the anchorage 238 on the link 231, urges the roller 234 into engagement with the cam 235 (Figure 13). Similarly, a coil spring 239 (Figure 12), secured at its upper end to the arm 222 and at its lower end to the frame 220, urges the cam roller 224 downwardly into engagement with the cam 225.

15 Also mounted upon the drive shaft 41 is a cam 240, the rearward edge of which is engaged by a roller 241 upon a stud 242, mounted on the slotted bar 243 through which the drive shaft 41 passes. The forward end of the slotted bar 243 is connected by the clevis 244 to the pivot pin 245 upon the arm 246. The latter is mounted upon the vertical shaft 247, journaled in the bosses 248 and 249 of the frame 220 (Figure 12). Mounted on the lower end of the vertical shaft 247 is a tucking arm or tucker 250. A collar 251 on the shaft 247 serves to retain the shaft in a fixed position vertically.

20

25

As a consequence of this construction, when the drive shaft 41 is rotated, the consequent rotation of the cam 225 causes the pressing member 228 and plunger 227 to be lowered, thereby pushing the sealed top of the bag 160 downwardly into the carton. As the pressing member 228 is shorter than the sealed mouth of the bag 160 (Figure 13), the ends thereof project and are forced upwardly and inwardly by the downward action of the presser 228 upon the central portion thereof. When the pressing member 228 reaches its lowermost position the tucker 250 moves into engagement with the trailing end flap, and pushes it and the adjacent end of the bag top inwardly and downwardly over the pressing member or tucker 228. At the same time the cam 235 now comes into operation to pull the link 231 and the pressing member 228 rearwardly with a wiping action. Meanwhile, a wedge-shaped tongue 252 is caused to move over the top of the carton 35, pushing the leading end flap and bag top portion downwardly before the pressing member or tucker 228 has moved away from the bag. The tongue 252 then holds down both carton end flaps while the carton 35 is moved by the conveyor to the top sealing station. The tapered end of the tongue 252 permits the member 228 to be withdrawn without permitting the end flaps to rise and open. After the member 228 is withdrawn, the tongue 252 moves completely over the carton top and its end flaps, holding them tightly down.

60 Operation of entire machine

At the start of operations the machine elements are in the positions shown in Figures 1 and 4. The operator starts the driving mechanism, 65 opens the valve 81 to permit gas, such as carbon dioxide, to flow into the pipe 80, fills the hopper 44 with the material to be packaged, such as coffee, and places a bag 160 in position upon the bag holder 61 beneath the spring clip 67. Car- 70 tons are fed into the pockets between the arms 34 of the conveyer at a loading station at the rear of the machine, and the bottoms are sealed at a bottom sealing station adjacent the carton-loading station, also at the rear of the machine.

75 The conveying chains 29 and 30 then convey

an empty carton to the filling station while the rods 117 and 118, by reason of their bent construction, open the side flaps of the carton. The end flaps, however, remain in their vertical positions. The rotation of the drive shaft 41 now causes the cam disc 43 and arm 54 to start the bag holder carriage 58 and bag holder 61 to move downwardly. At this time the bent portions 64 of the cam grooves 63 move the bag holder frame 66 from its forwardly projecting position (Figure 10) into its vertical position (Figure 3).

Meanwhile, the coffee or other material has been measured out and fed into the bucket 116, which now opens under the influence of the cam 141 (Figure 5), permitting the material to flow out of the bucket 116 against the guard 143, and through the receiver 142 and funnel 144, into the bag 160, as the bag 160 descends into the carton 35. The gas is timed by the cam 78 and valve 72 to commence to flow into the bag 160 while the bag holder frame 66 moves downwardly into the carton 35. When the bag 160 reaches the bottom of the carton, the bag-holding frame 66 dwells there a specified time, such as one and one-half seconds. At any desired point on the upward stroke, such as one-half of the height of the carton, the cam 78 closes the gas valve 72 and cuts off the flow of the gas. Thus, gas flows into the bag from the moment the bag holder frame 66 reaches its vertical position, until it has descended into the carton 35 and the material has filled the bag, the gas flow being cut off only after the bag-holding frame 66 has moved upwardly a part of its stroke.

The bag 160 and carton 35 thus filled with the material, are now moved to the sealing station by the intermittently timed action of the conveyor chains 29 and 30. The carton halts at the sealing station and the cam 180 on the drive shaft 41 causes the inverted T-frame 168 to be lowered, thereby lowering the bag-distending fingers 172 into the open mouth of the bag 160. As the fingers 172 approach the lowermost limit of their travel, they are moved outwardly by the projections 177 upon the vertical cam members 176 (Figure 10), thereby distending the mouth of the bag in a longitudinal direction and causing the open mouth to assume the shape of a long narrow slit.

The cam 180 now causes the frame 168 and 50 fingers 172 to be raised, pulling them out of the bag at the same time that the spring 199 causes the sealing elements 202 and 203 to move together. The bag-distending fingers by their distending action meanwhile have forced out much 55 of the gas remaining in the mouth of the bag. The arcuate motion of the sealing elements 202 and 203 toward one another causes much of the remaining gas to be expelled from the mouth of the bag as the sealing elements 202 and 203 engage the neck of the bag 160. As the sealing elements 202 and 203 reach their positions of nearest approach, as regulated by the screws 204 and 205 (Figure 8), the neck of the bag is tightly compressed between the projection 207 and depression 206, bringing the opposite inner walls of the bag into contact. The heating elements within the sealing elements 202 and 203 now cause the bag walls to become united and sealed, and the top of the bag assumes the form of a 70 long sealed thin edge.

The cam 198 now causes the sealing elements 202 and 203 to separate, resuming the position shown in Figure 7, whereupon the conveyor chains 29 and 30 again resume their intermit- 75

tent motion and convey the carton 35 and sealed bag 160 to the tucking station. At the tucking station the conveyor chains 29 and 30 halt, whereupon the cam 225 on the drive shaft 41 rotates to lower the arm 222, the plunger 227 and the pressing member 228 into engagement with the top of the bag 160. The pressing member 228 forces the central portion of the bag top downwardly into the carton, as a result of which 10 the ends thereof rise.

The cam 240 now comes into operation to bring the tucker 250 into engagement with the trailing end flap of the carton 35, forcing it and the trailing edge of the bag top inwardly and downwardly 15 upon the pressing member 228. Meanwhile, the tongue 252 moves toward the carton 35 and pushes down the leading end flap and bag top tuck toward the pressing member 228. The cam 235 now comes into operation to pull the link 231, 20 plunger 227 and presser 228 rearwardly, withdrawing the presser 228 by a wiping action from beneath the trailing end flap of the carton 35. As the cam 235 completes the rearward motion 25 of the pressing member 228, thereby completely withdrawing the pressing member 228 from the mouth of the carton 35, the cam 225 causes the arm 222, plunger 227 and presser 228 to be raised into the position shown in Figure 12. At this time the tongue 252 has moved completely over 30 the carton top and holds down the two end flaps tightly, the tapered end of the tongue 252 permitting the pressing member 228 to be withdrawn, but at the same time prevents the end flaps from opening up again.

35 Meanwhile, the tucker 250 is moved rearwardly into its withdrawn position (Figure 13) by the action of the cam 240. The carton 35 is then moved by the conveyor forwardly from the tucking station, its end flaps still held down 40 by the tongue 252. The side flaps of the carton have meanwhile been held open by the rods 117 and 118, and continue to be held open until they pass from beneath the ends of the rods, shown in Figure 3. Beyond the ends of the rods 45 117 and 118 the carton passes into further mechanism, shown in Figure 4, and forming no part of the present invention. By this subsequent mechanism the side flaps are moved inwardly and downwardly over the end flaps as they 50 emerge from beneath the wedge-shaped member 252, and adhesive is applied, and the carton itself is thus sealed.

It will be understood that we desire to comprehend within our invention such modifications 55 as come within the scope of the claims and the invention.

Having thus fully described our invention, what we claim as new and desire to secure by Letters Patent, is:

60 1. In a packaging machine, a filling station, means at said filling station for flushing out a bag with a gas other than air, means at said filling station for filling the bag with the material to be packaged, a sealing station, means for moving the bag from said filling station to said sealing station, means at said sealing station for sealing the mouth of the bag, a tucking station, means for moving the bag from the sealing station to the tucking station, means at 65 said tucking station for pressing the central portion of the sealed bag mouth toward the bag, and means at said tucking station for tucking inwardly the end portions of the sealed bag mouth.

70 75 2. In a packaging machine, a bag container

holder, a bag holder, means for inserting a bag into a container held by said container holder comprising means for moving said bag holder into and out of the bag container, means for flushing out the bag with a gas other than air, and means for filling the bag with the material to be packaged.

3. In a packaging machine, a bag container holder, a bag holder, means for inserting a bag into a container held by said container holder comprising means for moving said bag holder into and out of the bag container, means for flushing out the bag with a gas other than air, and means synchronized with the entry of the bag holder into the bag container for filling the bag with the material to be packaged.

4. In a packaging machine, a bag container holder, a bag holder, means for inserting a bag into a container held by said container holder comprising means for moving said bag holder into and out of the bag container, means for flushing out the bag with a gas other than air, means for filling the bag with the material to be packaged, and means synchronized with the departure of the bag holder from the bag container for cutting off the flow of the flushing gas.

5. In a packaging machine, a bag container holder, a bag holder, means for inserting a bag into a container held by said container holder comprising means for moving said bag holder into and out of the bag container, means for flushing out the bag with a gas other than air, means synchronized with the entry of the bag holder into the bag container for filling the bag with the material to be packaged, and means synchronized with the departure of the bag holder from the bag container for cutting off the flow of the flushing gas.

6. In a packaging machine, means for measuring out a predetermined quantity of the material to be packaged, a bag container holder, means for inserting a bag into a container held by said holder comprising a bag holder, means for moving said bag holder into and out of the bag container, means for flushing out the bag with a gas other than air, and means for filling the bag with the measured quantity of material to be packaged.

7. In a packaging machine, means for measuring out a predetermined quantity of the material to be packaged, a bag container holder, means for inserting a bag into a container held by said holder comprising a bag holder, means for moving said bag holder into and out of the bag container, means for flushing out the bag with a gas other than air, means for filling the bag with the measured quantity of material to be packaged, and means synchronized with the motion of said bag holder for regulating the admission thereto of said measured quantity of material.

8. In a packaging machine, a frame, a shaft rotatable in said frame, a bag holder, including means for introducing gas into a bag, a gas reservoir connected to said bag holder, a valve interposed between said gas reservoir and said bag holder, and means responsive to a predetermined rotation of said shaft for moving said valve to govern the flow of gas from said gas reservoir to said bag holder.

9. In a packaging machine, a frame, a shaft rotatable in said frame, a bag holder, including means for introducing gas into a bag, a gas reservoir connected to said bag holder, a valve

- interposed between said gas reservoir and said bag holder, and a cam on said shaft responsive to a predetermined rotation of said shaft for moving said valve to govern the flow of gas from 5 said gas reservoir to said bag holder.
10. In a packaging machine, a frame, a shaft rotatable in said frame, a container holder, and means for inserting a bag into a container held by said holder comprising a bag holder, means for introducing gas into said bag, a gas reservoir connected to said bag holder, a valve interposed between said gas reservoir and said bag holder, means responsive to a predetermined rotation of said shaft for moving said valve to govern the flow of gas from 10 said gas reservoir to said bag holder, and means for moving said bag holder into and out of a bag container.
11. In a packaging machine, a frame, a shaft rotatable in said frame, a container holder, and means for inserting a bag into a container held by said holder comprising a bag holder, means for introducing gas into said bag, a gas reservoir connected to said bag holder, a valve interposed between said gas reservoir and said bag holder, a cam on said shaft responsive to a predetermined rotation of said shaft for moving said valve to govern the flow of gas from 15 said gas reservoir to said bag holder, and means for moving said bag holder into and out of a bag container.
12. In a packaging machine, a frame, a shaft rotatable in said frame, a container holder, and means for inserting a bag into a container held by said holder comprising a bag holder, means for introducing gas into said bag, a gas reservoir connected to said bag holder, a valve interposed between said gas reservoir and said bag holder, means responsive to a predetermined rotation of said shaft for moving said valve to govern the flow of gas from 20 said gas reservoir to said bag holder, and means for moving said bag holder into and out of a bag container.
13. In a packaging machine, a frame, a shaft rotatable in said frame, a container holder, and means for inserting a bag into a container held by said holder comprising a bag holder, means for introducing gas into said bag, a gas reservoir connected to said bag holder, a valve interposed between said gas reservoir and said bag holder, a cam on said shaft responsive to a predetermined rotation of said shaft for moving said valve to govern the flow of gas from 25 said gas reservoir to said bag holder, and a second cam on said shaft for moving said bag holder into and out of a bag container.
14. In a packaging machine for packaging material in bags, means for elongating the mouth of the bag, a container holder and means for inserting a bag into a container held by said holder comprising means for sealing the elongated mouth of the bag.
15. In a packaging machine for packaging material in bags, means for elongating the mouth of the bag, means for depressing the elongated mouth of the bag and means for applying pressure to close the elongated mouth of the bag.
16. In a packaging machine for packaging material in bags, means for elongating the mouth of the bag, a container holder, a means for inserting a bag into a container held by said holder comprising means for applying pressure 75 to close the elongated mouth of the bag, and means for applying heat to seal the closed elongated mouth of the bag.
17. In a packaging machine for packaging material in bags, means for elongating the mouth of the bag, a container holder, a means for inserting a bag into a container held by said holder comprising means for applying pressure to close the elongated mouth of the bag, and means for bending the neck of the bag in a zig-zag form while applying pressure to close the elongated mouth thereof. 5
18. In a packaging machine for packaging material in bags, means for elongating the mouth of the bag, a container holder, a means for inserting a bag into a container held by said holder comprising means for applying pressure to close the elongated mouth of the bag, means for bending the neck of the bag in a zigzag form while applying pressure to close the elongated mouth thereof, and means for applying heat to seal the closed elongated mouth of the bag. 10
19. In a packaging machine for packaging material in bags, means for elongating the mouth of the bag, a container holder, a means for inserting a bag into a container held by said holder comprising means for sealing the elongated mouth of the bag, and means responsive to the completion of the elongation of the mouth of the bag for withdrawing the elongating means from the bag and applying the sealing means. 15
20. In a packaging machine for packaging material in bags, means for elongating the mouth of the bag, a container holder, a means for inserting a bag into a container held by said holder comprising means for sealing the elongated mouth of the bag, means responsive to the completion of the elongation of the mouth of the bag for withdrawing the elongating means, and means for moving the elongating means into 20 different positions in response to the withdrawal thereof from the bag. 30
21. In a packaging machine for packaging materials in bags, a frame, a shaft rotatable in said frame, a plurality of bag-mouth-elongating members, a support for said elongating members, means responsive to the rotation of said shaft for moving said support toward the bag, means for moving said bag-elongating members into their bag-elongating positions, and to cause the elongating members to descend a distance to lower the top of the bag. 35
22. In a packaging machine for packaging materials in bags, a frame, a shaft rotatable in said frame, a plurality of bag-mouth-elongating members, a support for said elongating members, means responsive to the rotation of said shaft for moving said support toward the bag, means responsive to the arrival of said bag-elongating members at the bag for moving said bag-elongating members into their bag-elongating positions, and to cause the elongating members to descend a distance to lower the top of the bag. 40
23. In a packaging machine for packaging materials in bags, a frame, a shaft rotatable in said frame, a plurality of bag-mouth-elongating members, a support for said elongating members, a cam responsive to the rotation of said shaft for moving said support toward the bag, means for moving said bag-elongating members 45 into their bag-elongating positions, and to cause the elongating members to descend a distance to lower the top of the bag.
24. In a packaging machine for packaging materials in bags, a frame, a shaft rotatable in 50

- said frame, a plurality of bag-mouth-elongating members, a support for said elongating members, a cam responsive to the rotation of said shaft for moving said support toward the bag, a second cam for moving said bag-elongating members into their bag-elongating positions, and to cause the elongating members to descend a distance to lower the top of the bag.
25. In a packaging machine for packaging materials in bags, a frame, a shaft rotatable in said frame, a plurality of bag-mouth-elongating members, a support for said elongating members, means responsive to the rotation of said shaft for moving said support toward the bag, means for moving said bag-elongating members into their bag-elongating positions, means for pressing together and sealing the elongated mouth of the bag, and to cause the elongating members to descend a distance to lower the top of the bag.
26. In a packaging machine for packaging materials in bags, a frame, a shaft rotatable in said frame, a plurality of bag-mouth-elongating members, a support for said elongating members, means responsive to the rotation of said shaft for moving said support toward the bag, means for moving said bag-elongating members into their bag-elongating positions and downwardly, means for pressing together and sealing the elongated mouth of the bag, and a cam responsive to a predetermined rotation of said shaft for actuating said pressing and sealing means.
27. In a packaging machine for packaging materials in bags, a frame, a shaft rotatable in said frame, a plurality of bag-mouth-elongating members, means for moving said members downwardly and laterally to spread the bag mouth and lower the spread portions simultaneously, a support for said elongating members, a cam responsive to the rotation of said shaft for moving said support toward the bag, a second cam for moving said bag-elongating members into their bag-elongating positions, means for pressing together and sealing the elongated mouth of the bag, and a third cam responsive to the rotation of said shaft for actuating said pressing and sealing means.
28. In a packaging machine for tucking sealed bags containing packaged materials, means for elongating the mouth of a bag and depressing it towards the remainder of the bag, means thereafter for sealing the adjacent walls of the bag so elongated and depressed, means for pressing the central portion of the sealed mouth of the bag toward the bag, and means for tucking the end portions of the bag inwardly toward the bag.
29. In a packaging machine for tucking sealed bags containing packaged materials, means for elongating the mouth of a bag and depressing it towards the remainder of the bag, means thereafter for sealing the adjacent walls of the bag so elongated and depressed, a presser for pressing the central portion of the sealed mouth of the bag toward the bag, means for tucking the end portions of the bag inwardly toward the bag, and means for withdrawing the presser from engagement with the bag.
30. In a packaging machine for tucking sealed bags containing packaged materials, means for elongating the mouth of a bag and depressing it towards the remainder of the bag, means thereafter for sealing the adjacent walls of the bag so elongated and depressed, a presser for press-
- ing the central portion of the sealed mouth of the bag toward the bag, means for tucking the end portions of the bag inwardly toward the bag, and means synchronized with the inward motion of said tucking means for withdrawing the presser from engagement with the bag.
31. In a packaging machine for tucking sealed bags containing packaged materials, means for elongating the mouth of a bag and depressing it towards the remainder of the bag, means thereafter for sealing the adjacent walls of the bag so elongated and depressed, a frame, a shaft rotatable in said frame, a presser, mechanism responsive to the rotation of said shaft for causing said presser to move the sealed mouth of the bag toward the bag, and means synchronized with the motion of said presser for tucking inwardly the end portions of the bag.
32. In a packaging machine for tucking sealed bags containing packaged materials, means for elongating the mouth of a bag and depressing it towards the remainder of the bag, means thereafter for sealing the adjacent walls of the bag so elongated and depressed, a frame, a shaft rotatable in said frame, a presser, mechanism responsive to the rotation of said shaft for causing said presser to move the sealed mouth of the bag toward the bag, means synchronized with the motion of said presser for tucking inwardly the end portions of the bag, and devices for withdrawing said presser from engagement with the bag.
33. In a packaging machine for tucking sealed bags containing packaged materials, means for elongating the mouth of a bag and depressing it towards the remainder of the bag, means thereafter for sealing the adjacent walls of the bag so elongated and depressed, a frame, a shaft rotatable in said frame, a presser, mechanism responsive to the rotation of said shaft for causing said presser to move the sealed mouth of the bag toward the bag, a tucker, and mechanism responsive to the rotation of said shaft for causing said tucker to tuck the end portions of the bag mouth inwardly toward the presser.
34. In a packaging machine for tucking sealed bags containing packaged materials, means for elongating the mouth of a bag and depressing it towards the remainder of the bag, means thereafter for sealing the adjacent walls of the bag so elongated and depressed, a frame, a shaft rotatable in said frame, a presser, mechanism responsive to the rotation of said shaft for causing said presser to move the sealed mouth of the bag toward the bag, a tucker, mechanism responsive to the rotation of said shaft for causing said tucker to tuck the end portions of the bag mouth inwardly toward the presser, and devices for withdrawing said presser from engagement with the bag.
35. In a packaging machine for tucking sealed bags containing packaged materials, a frame, a shaft rotatable on said frame, bag spreading fingers, means to move said fingers downwardly and laterally, means to thermoplastically seal the mouth of said bag in its spread and lowered condition, a presser, a cam responsive to the rotation of said shaft for causing said presser to move the sealed mouth of the bag toward the bag, a tucker, and a second cam responsive to the rotation of said shaft for causing said tucker to tuck the end portions of the bag mouth inwardly toward the presser.
36. In a packaging machine for tucking sealed bags containing packaged materials, a frame, a

shaft rotatable on said frame, bag spreading fingers, means to move said fingers downwardly and laterally, means to thermoplastically seal the mouth of said bag in its spread and lowered condition, a presser, a cam responsive to the rotation of said shaft for causing said presser to move the sealed mouth of the bag toward the bag, a tucker, a second cam responsive to the rotation of said shaft for causing said tucker to 5 tuck the end portions of the bag mouth inwardly toward the presser, and a third cam responsive to the rotation of said shaft for withdrawing said presser from engagement with the bag.

37. In a packaging machine for tucking sealed bags containing packaged materials, a frame, a shaft rotatable on said frame, bag spreading fingers, means to move said fingers downwardly and laterally, means to thermoplastically seal the mouth of said bag in its spread and lowered condition, a presser, a cam responsive to the rotation of said shaft for causing said presser to move the sealed mouth of the bag toward the bag, a tucker, a second cam responsive to the rotation of said shaft for causing said tucker to 10 tuck the end portions of the bag mouth inwardly toward the presser, and a third cam responsive to the rotation of said shaft for withdrawing said presser from engagement with the bag by a wiping motion relatively to the mouth of the bag.

38. In a method of packaging material in a collapsible bag within a carton, the step (a) of measuring a charge of material; the step (b) of expanding a collapsible bag; the step (c) of flushing air from the bag with an inert gas and introducing said bag into a carton; and the step (d) of permitting the measured charge of material to flow into the bag as it enters the carton.

39. In a method of packaging material in a collapsible bag within a carton, the step (a) of measuring a charge of material; the step (b) of expanding a collapsible bag; the step (c) of flushing air from the bag with an inert gas and introducing said bag into a carton; the step (d) of permitting the measured charge of material to flow into the bag as it enters the carton; the step (e) of spreading the mouth of the bag laterally to bring the walls thereof in parallel and depressing said walls towards the carton; and the step (f) clamping the walls of the bag so brought together and thermoplastically sealing them while in their depressed elongated condition.

40. In a method of packaging material in a collapsible bag within a carton, the step (a) of measuring a charge of material; the step (b) of expanding a collapsible bag; the step (c) of flushing air from the bag with an inert gas and introducing said bag into a carton; the step (d) of permitting the measured charge of material to flow into the bag as it enters the carton; the step (e) of spreading the mouth of the bag laterally to bring the walls thereof in parallel and depressing said walls towards the carton; the step (f) clamping the walls of the bag so brought together and thermoplastically sealing them while in their depressed elongated condition; and the step (g) of tucking the end portions of the bag mouth so sealed and sealing the carton.

41. In a packaging machine for inserting a bag into a carton, means for measuring a charge of material, means for supporting and mechanically expanding the bag, means associated with both of said means for introducing an inert gas into the bottom of the bag, means for moving said

bag, expanding and supporting means, and inserting the bag into a carton, means for admitting inert gas and said material into the bag as it is inserted into the carton, and means for timing the mechanical expansion of the bag, its insertion into a carton and the admission during said insertion of inert gas and material so that as the mechanical expanding means and gas supplying means are withdrawn, the filling of the bag in the carton is completed.

42. In a packaging machine for inserting a bag into a carton, means for measuring a charge of material, means for supporting and mechanically expanding the bag, means associated with both of said means for introducing an inert gas into the bottom of the bag, means for moving said bag, expanding and supporting means, and inserting the bag into a carton, means for admitting inert gas and said material into the bag as it is inserted into the carton, means for timing the mechanical expansion of the bag, its insertion into a carton and the admission during said insertion of inert gas and material so that as the mechanical expanding means and gas supplying means are withdrawn, the filling of the bag in the carton is completed, means for moving the filled bag and carton from the filling station to a bag extending station, a bag extending station, and means thereat for extending the mouth of said bag and moving said mouth downwardly toward said carton.

43. In a packaging machine for inserting a bag into a carton, means for measuring a charge of material, means for supporting and mechanically expanding the bag, means associated with both of said means for introducing an inert gas into the bottom of the bag, means for moving said bag into a carton, means for admitting inert gas and said material into the bag as it is inserted into the carton, means for timing the mechanical expansion of the bag, its insertion into a carton and the admission during said insertion of inert gas and material so that as the mechanical expanding means and gas supplying means are withdrawn, the filling of the bag in the carton is completed, means for moving the filled bag and carton from the filling station to a bag extending station, a bag extending station, means thereat for extending the mouth of said bag and moving said mouth downwardly toward said carton, means for moving the carton with the bag mouth so extended to a sealing station, and means at said sealing station for engaging the parallel extended side walls of said bag mouth in their lowered position to seal thermoplastically said mouth.

44. In a packaging machine for inserting a bag into a carton, means for measuring a charge of material, means for supporting and mechanically expanding the bag, means associated with both of said means for introducing an inert gas into the bottom of the bag, means for moving said bag into a carton, means for admitting inert gas and said material into the bag as it is inserted into the carton, means for timing the mechanical expansion of the bag, its insertion into a carton and the admission during said insertion of inert gas and material so that as the mechanical expanding means and gas supplying means are withdrawn, the filling of the bag in the carton is completed, means for moving the filled bag and carton from the filling station to a bag extending station, a bag extending station, means thereat for extending the mouth of said bag and moving said mouth downwardly toward said carton.

- ton, means for moving the carton with the bag mouth so extended to a sealing station, means at said sealing station for engaging the parallel extended side walls of said bag mouth in their lowered position to seal thermoplastically said mouth, means for moving said sealed bag and carton to a tucking station, and means for tucking inwardly the end portions of the sealed bag mouth.
- 10 45. In a packaging machine for inserting a bag into a carton, means for measuring a charge of material, means for supporting and mechanically expanding the bag, means associated with both of said means for introducing an inert 15 gas into the bottom of the bag, means for moving said bag into a carton, means for admitting inert gas and said material into the bag as it is inserted into the carton, means for timing the mechanical expansion of the bag, its insertion 20 into a carton and the admission during said insertion of inert gas and material so that as the mechanical expanding means and gas supplying means are withdrawn, the filling of the bag in the carton is completed, means for moving the 25 filled bag and carton from the filling station to a bag extending station, a bag extending station, means thereat for extending the mouth of said bag and moving said mouth downwardly toward said carton, means for moving the carton with 30 the bag mouth so extended to a sealing station, means at said sealing station for engaging the parallel extended side walls of said bag mouth in their lowered position to seal thermoplastically said mouth, means for moving said sealed bag 35 and carton to a tucking station, means for tucking inwardly the end portions of the sealed bag mouth, means for moving the tucked and sealed bag and carton to a carton sealing station, and means for sealing the carton thereat.
- 40 46. In a packaging machine, the combination of means for holding a bag, spreading fingers adapted to be inserted in the mouth of said bag to bring the walls at the top thereof in parallel as the bag mouth is spread, and means for moving 45 said fingers toward the body of the filled bag to move the spread walls of the bag mouth downwardly to position them in parallel in a lowered spread condition.
47. In a packaging machine, the combination 50 of means for holding a bag, spreading fingers
- adapted to be inserted in the mouth of said bag to bring the walls at the top thereof in parallel as the bag mouth is spread, means for moving said fingers toward the body of the filled bag to move the spread walls of the bag mouth downwardly to position them in parallel in a lowered spread condition, and means for clamping said parallel bag walls in their lowered position and thermoplastically sealing them after the withdrawal of said fingers. 5
48. In a packaging machine, the combination of means for holding a bag, spreading fingers adapted to be inserted in the mouth of said bag to bring the walls at the top thereof in parallel as the bag mouth is spread, means for moving said fingers toward the body of the filled bag to move the spread walls of the bag mouth downwardly to position them in parallel in a lowered spread condition, means for clamping said parallel bag walls in their lowered position and thermoplastically sealing them after the withdrawal of said fingers, and means for timing said bag spreading and lowering means and said sealing means to successively operate on said bag. 10 15 20
49. In a packaging machine, a bag holder comprising laterally movable bag expanding members and a pipe interposed therebetween extending to the bottom of the bag centrally thereof but above the ends of said bag expanding members. 25
50. In combination, in a packaging machine, of means for measuring a charge of material to be loaded into a bag, means for delivering said material at a time interval progressively by gravity into the bag, means for supplying inert gas at the interior of the bag, means for mechanically expanding said bag around the end of the gas-supplying means and in line with the material-supplying means, means for moving said bag, expanding means and gas-supplying means with the bag while connected to the material-supplying means into a carton, and means for regulating the supply of gas and material to said bag as it enters said carton and as the expanding means and gas-supplying means are withdrawn from the bag after it has been located in the carton.
